UNITED STATES PATENT OFFICE.

ISAAC N. FORBES, OF NEW YORK, N. Y.

LASTING-MACHINE.

SPECIFICATION forming part of Letters Patent No. 436,853, dated September 23, 1890.

Original application filed July 13, 1889, Serial No. 317,443. Divided and this application filed December 13, 1889. Serial No. 333,685. (No model.)

To all whom it may concern:

Be it known that I, ISAAC N. FORBES, a citizen of the United States, residing at New York, in the county of New York and State of New York, have invented certain new and useful Improvements in Lasting-Machines; and I do declare the following to be a full, clear, and exact description of the invention, such as will enable others skilled in the art to which it appertains to make and use the same.

My invention relates to improvements in various parts of such a machine, especially in the operating or power mechanism in the side-lasting clamp carriers and levers, and in the table, with a view to simplifying, lightening, and cheapening its construction, while at the same time the convenience and efficiency of its operation are increased.

My invention consists in those parts and combinations thereof, or their equivalents, which are hereinafter set forth and claimed.

With regard to the side-lasting clamps and holders therefor, this application is a division of that filed by me July 13, 1889, Serial No. 317,443.

In order to make my invention more clearly understood, I have shown in the accompanying drawings means for carrying the same into practical effect.

In said drawings, Figure 1 is an end view, partly in vertical section, of a lasting-machine embodying my invention, the base of the table being broken away. Fig. 2 is a side view, partly in section, of the same. Fig. 3 is a bottom plan view, partly in section, of the table. Fig. 4 is a side view, partly in section, of one of the lasting-finger carriers or clamp-tubes. Fig. 5 shows an end view of the last clamp-piece, a longitudinal section of the same, and a side and outer face view of the end bearing-piece. Fig. 6 is a bottom plan view of the table without the actuating mechanism. Fig. 7 is a longitudinal section on line 7 7, Fig. 6. Fig. 8 is a vertical sectional view on line 8 8, Fig. 3. Fig. 9 is a vertical sectional view on line 9 9, Fig. 3. Fig. 10 is a similar view on line 10 10, Fig. 3. Fig. 11 is a bottom plan view of a portion of the table. Figs. 12, 13, and 14 are edge views of the covering-plate for the same. Fig. 15 is a bottom

plan view of one of the screw sleeves or nuts by which the end levers are actuated. Figs. 16 and 17 are views from the opposite ends of the same. Figs. 18 and 19 are respectively a plan and end view of the other screw sleeve or nut. Fig. 20 is a transverse sectional view, part full, showing a portion of the table and a modified form of side-clamp carrier and carrier-holder. Fig. 21 is an elevation, partly in section, on line 21 21, Fig. 20. Fig. 22 shows, by side and end views, on a larger scale, the stop-screw of the oscillating side-clamp holders. Fig. 23 is an end view, partly broken away, of the lasting-machine table with the mechanism removed. Fig. 24 is a front view, partly broken away, of the same. Fig. 25 is a horizontal sectional view on line 25 25 of Fig. 24. Fig. 26 is a plan view of a portion of one of the frames which stiffen and connect the table-legs and are adapted to support the shelves. Fig. 27 is a sectional view of the same. Figs. 28 and 29 are transverse sectional views illustrating different means of stiffening and supporting the shelves.

Table.—Referring to the drawings, A indicates the table, designed especially to meet the various requirements of this machine, both for the support and adjustment of the various parts of the frame and mechanism and for the reception of the detachable and interchangeable parts when not in use. The table is provided around its edge with a depending flange a , transverse arched bearing-plates $a' a'$, and strengthening-plates $a^2 a^2$, situated below the top of the table and within the flange a , horizontal perforated end-clamping flanges a^3 , joined to the lower edges of flange a and plates a' , lateral extensions $A' A'$ to accommodate and inclose the side-lever mechanism and having depending flanges a^4 , longitudinal arched bearing-plates a^5 between the extensions A' and the body of the table and cut away at a^{14} , vertically-perforated bearing-bosses $a^6 a^6$, depending from the top of the table, and eccentrically situated, as shown in Figs. 2 and 6, a longitudinal central enlargement a^7 , formed upon the under side of the table-top and containing the longitudinal T-groove a^8 , a central depending longitudinally-perforated bearing-bracket a^9 ,

and longitudinal guides a^{18} . All of these parts are preferably formed by a single casting, although they may consist of several parts bolted together. The table-top is vertically and centrally slotted transversely, as indicated at $a^{10} a^{10}$, and longitudinally, as shown at $a^{11} a^{11}$, to admit of the passage and working of the side and end lasting levers. The middle portion of groove a^8 is enlarged, as indicated at a^{12} , and the lower and wider part of the same is still further and circularly undercut at a^{13} . $A^2 A^2$ indicate the legs of the table. They consist of sheet metal screwed or riveted at their upper ends to the flanges a^{15} of castings A^{11} , of a width equal to that of the main portion of the table and provided with horizontal perforated top flanges a^{16} , which fit and are secured to the under side of flanges a^8 by bolts a^{17} . At their lower ends the sheet-metal legs A^2 are riveted or screwed to castings A^{12} , which form the basis of the whole structure. At various heights sheet-metal shelves A^3 , which have upturned edge flanges a^{19} , are fastened by rivets or screws a^{20} to the vertical portions of the legs. These shelves serve to hold the interchangeable parts of the machine within convenient reach of the operator, and are so disposed that the desired part may be readily selected.

It is highly important that the operator of each machine have under his absolute control the interchangeable parts of his machine, not only conveniently arranged and within easy reach, as already mentioned, but so secured that in his absence other workmen may not borrow or abstract these easily portable pieces. This despoiling of a machine is always a source of annoyance and delay, and is sometimes resorted to for the purpose of bringing a particular workman or type of machine into disrepute. I have therefore provided the working parts of the machine with a substructure, which is in effect a metallic safe, within which the detachable parts of the machine may be not only conveniently but securely stored.

Referring to Figs. 23 to 29, A^4 indicates a horizontal frame, which fits between the side flanges a^{32} or vertical portions of the sheet-metal legs A^2 and is firmly riveted or screwed to said legs, thereby producing a very rigid though light structure. Upon said frame is supported the lowermost of the shelves A^3 . In the construction shown the frame A^4 is provided with an upwardly-extending flange a^{21} , over which the edges of the said shelf are bent and secured, Fig. 28. Between the edges of the vertical portions of the two opposing legs A^2 said frame is provided with a horizontal outwardly-extending flange a^{31} , Fig. 26, the ends of which extend for a short distance horizontally and longitudinally into the material of the side flanges of the legs, which latter are cut away a corresponding distance for this purpose. The inner vertical edges of said leg-flanges are bent inward, Fig. 25, to form a recess or rabbet upon both the rear

and front of the table, as shown, respectively, at $a^{22} a^{23}$, in which rabbets fit a back plate A^6 , which is permanently secured in place, and a door or doors A^7 . The latter are hinged at A^8 and are provided with a lock A^9 . Around the ends of the frame A^4 and filling the space between the frame and the sheet-metal legs is a strip a^{24} , which may be riveted or soldered in place. The interior of the legs is provided with a horizontal supporting-flange a^{25} —one at each end of the table—upon which rests the intermediate shelf A^3 . As many of such flanges and shelves may be provided as are deemed necessary for the storage of the detachable parts of the machine. The shelves which are carried by the flanges or plates a^{25} may be of any desired character. As shown in Fig. 29, they may be stiffened by strips or frames A^5 , around which the edges of the shelves are bent. Near their lower ends the edges of the side flanges of the legs are bent inward at a^{26} , forming flanges, which may be curved or arched, as shown in Fig. 24, and which are connected by similarly-shaped transverse plates a^{27} , which are permanently riveted, soldered, or otherwise secured to said flanges. The lower ends of the legs thus formed fit over and around the upwardly-extending flanges a^{28} of the base-castings A^{12} and rest upon the shoulders a^{29} of the latter. Screws or bolts may be used for connecting the legs, the back plate, the shelves, and the frame A^4 together, and the whole structure thus rendered easily separable for transportation. Rabbets a^{30} are formed upon or in the depending flanges of the table-top to correspond with the rabbets $a^{22} a^{23}$.

B and D indicate, respectively, the heel and toe stands, of any preferred or suitable character, upon which is supported the last C.

E E indicate two yoke and side fulcrum stands mounted at the sides of the table upon the extensions A' and secured rigidly in place by vertical bolts e , the heads and nuts of which engage the under side of the table-top and the upper surfaces of the horizontal flanges e' of the stands. With said flanges and the outer walls of the stands are cast horizontal transverse bearings e^2 , which are vertically and longitudinally slotted and provided at their outer ends with internally screw-threaded bushings E' , which are screwed in place in the stands, Fig. 1. Above the flanges e' the stands E extend outwardly and upwardly, Fig. 1, being U-shaped in horizontal cross-section, with the open or concave side inward, and upon their tops are mounted posts $E^2 E^3$. The former constitutes a vertical pivot, upon which fit sleeves $f f'$ of the hinge-piece F of the head-yoke F', which sleeves rest upon the flange e^5 of the post, and are engaged by a nut e^6 , screwed upon the upper end of the post, respectively. The hinge-piece has two inwardly-extending ears f^2 , between which the yoke F' fits, and on which it is mounted by means of a horizontal hinge-pin f^3 , which fits both of the parts neatly, and

by a stop-pin or bolt f^4 , which fits neatly the ears of the hinge-piece and engages a slot f^5 , formed from pin f^3 as a center in the yoke F' .

F^2 is a plate-spring mounted between the ears f^2 on a pin f^6 , engaging by its free end a notch f^7 in the yoke and bearing between its ends and by its inner face against a pin f^8 . These parts are so adjusted that the spring F^2 has the necessary tension to lift the yoke F' , with its head and pliers, (when the latter are disengaged from the upper,) oscillating the yoke upon pin f^3 upward and outward until the inner end of slot f^5 strikes the stop-pin f^4 . When thus lifted, the yoke with its head may be easily swung upon post E^2 from over the last to the position indicated in Figs. 1 and 2, thus affording ready access for securing the upper and removing the lasted shoe. The severe lifting strain imposed upon the workman by the ordinary upwardly-lifting turning head is thus entirely obviated.

G is the downhold, comprising a head g , adapted to rest upon the inner sole and swiveled upon a screw-threaded stem g' . The latter engages and is vertically adjustable in a bracket G' , which latter has a journal g^3 fitting a vertical bearing f^{16} in the arch f^{17} of the head-yoke, where it is secured by a nut g^4 .

Head.—The pliers K are preferably so constructed and supported that after they have been engaged with the edge of the upper they may all be raised at once by crank I to draw the upper tightly over the last; but any suitable form of plier and supporting and operating devices therefor may be employed.

End-lasting devices.—The upper having been stretched and drawn up properly over the last in a well-known manner, the lasting devices or clamps begin their operation. I will now describe my improvements in these parts of the machine and in the means whereby they are supported and actuated.

N N' represent the heel and toe lasting clamp-stands, provided at their bases with T -bolts n , adapted to fit the table-groove a^8 , and with nuts n' , engaging said bolts, by which the stands may be rigidly secured in place when properly adjusted. Except for extreme sizes of last, these stands will not require to be moved. At their upper ends the stands are provided with horizontal longitudinal clamp-bearings n^2 n^3 , adapted to be compressed by hand-screws n^8 upon slide bearing-sleeves N^2 N^3 , which latter may thus be longitudinally adjusted and securely held.

N^4 N^4 indicate slide-shafts fitting and freely movable endwise within the said sleeves and having near their inner ends vertical mortises n^4 . At their extreme inner ends the slides are provided with curved clamp-guides n^5 , which are compressible by hand-screws n^6 upon correspondingly-shaped curved slides N^5 . The latter are provided with inwardly-extending perforated ears n^7 , between which are mounted the heel and toe lasting jaws N^6 N^7 , hinged on pins n^8 , which pass through the perforations of the ears n^7 and through

bearings in the jaws. The slides N^5 are circularly adjustable in vertical longitudinal planes in the clamp-guides n^5 to adapt the end jaws to the forward and rearward slants of the bottom of the last. The outwardly-extending arms n^{11} of the end-lasting jaws are provided with balls n^9 , which are connected with stationary balls n^{10} , rigidly secured to the sleeves N^2 N^3 . Links O , provided with suitable sockets for said balls, connect the arms of the jaws with parts of the machine which are thus stationary. When, therefore, the jaws are by slides N^4 bodily moved inward, they are caused to simultaneously close by reason of their arms being held back by the said links O .

P P are the end levers, which actuate the slides N^4 and give to the end-lasting jaws the movements already described. Said levers are mounted and turn upon horizontal transverse fulcrum-pins p , and at both their upper and lower ends are formed with circular eyes p' p^2 p^2 . The eyes p^2 are formed upon each of the two forks p^8 of the lower end of the lever and fit and turn in socketed side pieces p^3 , with which they are also connected by central pins p^4 , and said side pieces fit neatly and are adapted to slide vertically in lateral recesses s' of the slide-nuts S S' , thus forming combined slide hinge-joints P^2 . The eyes p' above the table have similar joints P' with the mortises n^4 of slides N^4 . The fulcrum-pins p are carried by the vertically-forked inner ends P^3 of longitudinally-adjustable end fulcrum-shafts P^4 , mounted in bearings N^8 , formed in the stands N N' . In the outer portions of the stands are screwed internally-threaded bushings N^9 , within which fit correspondingly-threaded screw-sleeves P^5 , provided with external milled heads or handles p^5 . Within these sleeves neatly fit the outwardly-extending stems p^6 of the shafts P^4 , which are held from inward movement from the sleeves by nuts P^6 , engaging the threaded ends of said stems and abutting against the outer faces of the sleeves P^5 . It will thus be seen that the end-lever fulcrums may be readily adjusted to suit the length of last by turning the sleeves P^5 , the shafts P^4 being prevented from turning by the engagement of the end levers with their forked ends P^3 . During this adjustment the screws n^8 are loosened.

Side-lasting devices and actuating mechanism.—The side-lasting clamp-levers are shown at R . They are mounted upon fulcrum-pins r , carried by slide-shafts R' , the latter being mounted in the bearings e^2 of the side stands E and adjustable by means of sleeves R^2 engaging the shafts R' and screwing in the bushings E' in a manner substantially similar to that already described in connection with the end levers. At their lower ends, below the table, side levers R are provided with slide hinge-joints R^3 , by means of which they connect with the mortises q of transverse slide-shafts Q Q . These shafts

are supported near their inner ends in bearing-bushings q' , screwed or driven into the plates a^5 and at their outer ends in tubular inclosed bearings q^6 , fitted in the outer flange a^4 and secured by nuts q^7 . The slide hinge-joints are formed by socket-pieces r' , which fit around the eye r^2 of the lever, with which they are also connected by pins r^8 , and fit and slide vertically in said mortises q . The nuts S S' , already referred to, are engaged by right and left threads S^2 S^3 , formed on a longitudinal power-shaft S^4 , the outer ends of which are mounted in bearing-tubes s^2 s^3 , fitted into the end flanges a a' of the table and clamped in place by nuts s^4 . Said shaft is further supported at the middle and held from endwise movement by being made in two parts screwed and pinned together, one of which has a journal s^5 , mounted in the bracket a^9 , and a boss s^6 and screw-threaded stem s^7 , which fit in the other part of the shaft. The bushing or bearing s^2 is provided with a set-screw s^8 , which bears against the end of shaft S^4 or against an interposed washer or packing, and is adapted to take up end-play. An oil-hole s^{14} , formed in the screw s^8 , and a similar hole s^{15} , formed in the other end of the shaft, enable both end bearings of the shaft to be readily lubricated. The slide-nut S is formed with lateral ears s^9 on each side thereof, which carry hinge-pins s^{10} . The latter engage eyes in the ends of links S^5 , which extend horizontally inward by the sides of shaft S^4 to a point where, by pins s^{11} , they are hinged to the lateral arms of an angle-levers S^6 by pins s^{12} . At their angles these levers are fulcrumed by bolts s^{13} to the lower ends of bosses a^6 , and their longitudinal arms extend inward to points in line with the transverse slide-shafts Q , to which they are connected by links Q' . It will therefore be seen that when the power-shaft S^4 is rotated in the proper direction (to the right in Fig. 3) the parts connected directly and indirectly therewith will be moved in the directions indicated by the arrows in said figure. The lower ends of both the side and end levers will be forced outward, and their upper ends, carrying the lasting-clamps, swing inward toward the last and force the clamps against the upper, which at such time will be held by the pliers. By arranging the power-shaft longitudinally, as thus shown, it is more readily manipulated by the crank S^7 , permitting the operator to assume such position at the side of the machine and close to its vertical line or axis that he may at the same time conveniently reach and turn the crank I , which lifts and lowers the head. This is of importance, for as the lasting devices are forced inward against the upper the strain on the latter is slightly eased off by simultaneously lowering the head, thus obtaining a most perfect lasting of the upper without injury to it.

Near their upper ends the side levers R are provided each with a transverse flange r^4 ,

above which the lever is continued in the form of a short screw-threaded stem r^5 , upon which is screwed a hollow socket-piece T . ^{7c} The latter is then for greater security fastened by a transverse pin t , Figs. 1, 20, and 21, which also holds in position an external sleeve T' , inclosing the lower cylindrical extension t' of the said socket-piece. On the inner side the said extension and sleeve are perforated, as shown at t^2 , and at t^3 t^4 , just above sleeve T' , the extension t' is perforated through both the inner and outer sides. In line with the perforations t^3 is situated a screw-stop-pin u , (shown separately in Fig. 22,) mounted and adjustable in the extension u' of the oscillatory holder U , also hollow. The length of the pin is equal to the external diameter of the extension t' . The upper part of the holder forms a hemispherical inner socket-piece u^2 , which fits accurately in a correspondingly-shaped portion t^4 of the outer piece T , and is secured in place and permitted to oscillate only in the transverse plane of the machine by hinge-bolts t^5 t^6 , Fig. 21, which pass through and have bearings in the sides of the socket t^4 and screw into the sides of the inner piece u^2 . A spring U' , held at its upper end in a split tapered plug u^3 , driven into a tapered hole in the hollow cylindrical extension u' and situated within said extension, bears at its lower free end against the inner end of a pin t^6 , which is screwed or otherwise secured in the wall of the outer side of extension t' , projecting inward through a perforation in the outer side of extension u' into the interior of the latter. The tension of the spring U' is such that it will always tend to force the lower end of the holder U inward and its upper end outward relative to the socket-piece T , thus elevating the inner ends or edges of the side-lasting clamps V , which are carried by said holder. In this position said lasting devices will pass inward over the edge of the last at a height just above the top surface of the inner sole. Having passed the edge of the latter, the clamps V are depressed tightly against the upper, moving at the same time slightly inward, and the lasting operation proper will be finished and the upper ready to be tacked or cemented in place. During this action of the lasting devices the head and pliers may be lowered slightly to yield a little of the upper to the lasting-clamps and prevent tearing of the material, the operator for this purpose easing off the crank I with his left hand, while with his right he rotates the power-crank S^7 . The said depression of the side clamps is effected by stop screws W W' , mounted and horizontally adjustable in eyes w w' and situated in line with the perforations t^2 , so that when the side levers are near the limit of their inward movement the outer ends of said screws will enter the perforations and arrest the extensions u' , Fig. 1. The eyes w are carried by a Y-frame W' , the lower portion of which is a cylindrical journal w' , vertically mounted and

swiveling in a bearing-sleeve W^2 . The latter has at its bottom a T -head w^2 , adapted to pass down through the enlargement a^{12} of the table-groove and, when turned crosswise, to fit the undercut portion a^{13} of the same. It is then clamped in place by a nut w^3 , which engages a thread on the sleeve and bears against a washer w^4 , which in turn rests upon the top surface of the table, Figs. 1 and 20.

5 The holder U is provided with an internal hemispherical socket, which is completed and adapted to form one member of a ball-and-socket joint by a screw-plug U^2 , suitably concaved on its inner face and screwed into the upper end of the holder. Within the socket thus formed are situated two hemispherical clamping-pieces U^3 , between which and half in each is formed a cylindrical clamp-bearing u^5 , adapted to receive the shank V' of the 15 side-clamp carrier. The latter may be formed with its shank substantially vertical or in line with the side lever, Fig. 1, or with the shank at right angles to the lever, Fig. 20, and therefore the clamping-pieces U^3 will be correspondingly arranged with their bearings u^5 in line with the shank V' . The clamping-pieces are forced together and upon the shank V' by means of a set-screw V^4 , which passes through and engages the holder or a portion 25 thereof, either horizontally, as in Fig. 1, or vertically, as in Fig. 20. In the former case the outer socket-piece T is provided with an aperture t^6 on its outer side to accommodate the set-screw. In the latter case the part of the 30 holder engaged directly by the threads of the screw V^4 will be the plug U^2 . If desired, a bearing-piece u^6 , Fig. 20, may be interposed between the screw U^4 and the clamping-piece U^3 to give a wider bearing on and obviate 35 any tendency to turn the latter.

40 U^5 , Fig. 1, is a screw engaging the holder-socket and projecting at its inner end into a recess u^7 , larger than the screw, which is formed in one of the clamping-pieces U^3 . This screw 45 prevents the clamp-bearing u^5 from being twisted away from the opening in the holder through which the shank V' enters. In Fig. 20 a similar office is performed by the upper end u^8 of plug u^3 .

50 It will be seen that by the parts described the side-lasting clamps are so mounted as to be universally adjustable in any direction within limits ample for the purpose, and can therefore be readily fixed in exactly the position necessary for their proper operation relative to the last. While so adjusting the clamps, they are brought forward against the last and should be rigid upon their levers. The stop-pin u , already referred to, is provided for this purpose, and is designed to act in conjunction with a sleeve T^8 , which encircles the extension t' below a flange t^8 and resting on the upper end of the fixed sleeve T' . While thus held in position vertically 65 opposite to the pin u , the sleeve T^8 may be readily rotated to bring its solid portion against the ends of said pin or to bring in

line with the same the openings t^9 . In the latter case the holder U may oscillate freely. In the former it will be rigidly held. The upper edge of the sleeve T^8 is cut away for about a quarter of a circle, forming a recess at t^{11} , the ends of which are engaged by a pin t^{10} , driven into the extension t' . In order that the fingers V^2 of the side-lasting clamps may lie substantially horizontal when the side levers are at the inner limit of their throw, I provide for mounting said fingers at an obtuse angle to the shank V' . Such obtuse angle is well seen in Figs. 1 and 20. In Fig. 1 the relation of the parts is such that the obtuse angle is necessarily between the upper sides of the fingers and shank, while in Fig. 20 the construction is such that said obtuse angle is between the lower sides of the fingers and the inner side of the shank.

With the actuating mechanism and with the side-lasting levers and holders above described other lasting-clamps than those herein shown and about to be described may be employed, as will be readily understood, without losing any of the advantages which are attained by my improvements in such mechanism; but by the side-lasting clamps illustrated I attain additional valuable results in the compactness and strength of the clamps and in their universal adaptability to any shape or size of lasts.

55 V^5 indicates a tube, which I term a "vise-clamp" tube, secured to or formed in the same piece with the shank V' . This tube is provided upon its inner side, and preferably also upon its outer side, with apertures v of larger diameter than the shanks or stems v' of the lasting-fingers and adapted to permit the entrance of said stems. Within said tube (which latter may obviously be made in the form of a partly-open frame) are situated a number of separate clamping-pieces v^2 , Fig. 4, which are provided between the contiguous faces of each pair with cylindrical bearings v^3 , one-half of the bearing being formed in each clamping-piece. Said bearings are situated opposite to or in line with the openings v , so as to be adapted to receive the stems v' , which latter they are shaped to fit. The clamping-pieces are adapted to be slightly moved or pressed longitudinally in the tube V^5 , being confined at one end by a screw or plug V^6 and being engaged at the other end by a clamping-screw V^7 . The latter preferably operates through the medium of a bearing-piece v^4 , which is provided on its outer face with a concavity v^5 , within which fits a corresponding convex portion of the screw V^7 , Figs. 4 and 5. Said bearing-piece is mounted within a socket v^6 , formed in the outer face of an end clamping-piece v^7 , and it will thus be seen that when the lasting-fingers have all been properly adjusted they may be simultaneously rigidly clamped by turning up the screw V^7 . In order to prevent any tendency to twist the clamping-pieces, so that their bearings v^3 will be turned out of line with the openings v , the

end clamping-piece v^7 is provided with one or more longitudinal grooves v^8 , which are engaged by corresponding pins v^9 , screwed or driven through the tube or frame and projecting at their inner ends into the said groove or grooves.

The lower side of the extensions A' is inclosed by a plate A^{10} , Figs. 11 to 14, which is secured in place by screws A^{11} and provided with vertical flanges A^{12} , which fit in and close the lower parts of the openings a^{14} , in which the ends of the angle-levers S^6 play. The operating mechanism is thus inclosed and protected from dust and dirt.

In adapting the machine to operate in conjunction with the particular shape and size of last which is to be employed the operation is as follows, referring especially to Fig. 1: The lasting devices being in the position in which they were left at the close of the previous lasting operation—that is to say, away from the last—the new last, having the insole and upper in place thereon, is placed upon the heel and toe stands. By means of the various adjusting devices with which the latter are provided the last is then brought into line with the end clamps and raised or lowered, as may be necessary, to the proper height relative thereto. During these adjustments of the last the lasting devices may by means of the power mechanism be caused to approach the last in order that the proper position of the same may be accurately determined. The clamp-screws n^3 having been slackened, the power-shaft S^4 is turned to cause the end clamps to abut against the ends of the last, this result being aided (in case of much variation in the lengths of the previous and present lasts) by turning the end fulcrum-screws P^5 and in extreme cases adjusting the end stands $N^2 N^3$ in the groove a^8 . The sleeves $N^2 N^3$ are then adjusted longitudinally in their bearings n^2 to such points that the end-lasting jaws $N^6 N^7$ will assume their closed position, whereupon the bearings n^2 will be caused to rigidly secure the sleeves $N^2 N^3$ by means of said screws n^3 . A pair of side-lasting clamp carriers having a set of lasting-fingers are then placed in position upon the side levers with their shanks inserted in the bearings u^5 . The sleeve T^8 having been turned, so as to engage both ends of the stop-pin u , so as to prevent the oscillation of the holder U , the operative ends or edges of the lasting-fingers are (by the power mechanism) brought approximately into contact with the upper, the screws V^7 are loosened, and the lasting-fingers are then adjusted accurately to the last by twisting their shanks in the bearings v^3 and by oscillating the clamps or pieces v^2 in the carrier, the carrier as a whole having been adjusted by turning its shank in the bearing u^5 and the clamping-pieces U^5 in their spherical socket. The carrier is rigidly secured by the screw V^4 , and the individual lasting-fingers are simultaneously clamped when satisfactorily adjusted

by means of the screw V^7 . By the combined operation of the power mechanism, of the side fulcrum-screws B^2 , and of the stop-screws W the parts are brought into such relative positions that when the nuts $S S'$ are in their outermost position abutted against the bushings or tubes $s^2 s^3$ the operative edges of the side-lasting clamps are in their final innermost position, with the screws W engaged with the lower ends of the holders and with the upper suitably stretched and lasted. The lasting-clamps being now retracted by the power mechanism and the sleeves T^8 being so turned as to permit the oscillation of the holders, the machine will be ready for any desired number of successive lasting operations in conjunction with the last for which the machine has been adjusted, as above described.

It will be noted that the inner ends of the bushings or bearing-tubes $s^2 s^3$ serve as positive stops, which limit the inward movements of the lasting devices beyond a certain point, thus preventing the possibility of injury to the upper or to the last.

Having thus described my invention, what I claim is—

1. In a lasting-machine, an adjustable lasting-finger carrier having a series of clamping-pieces bearing one against the other and adapted to receive and hold a plurality of adjustable lasting-fingers and provided with a shank at an obtuse angle to the bearings for said fingers and with means for forcing said pieces against one another and against the finger-shank, substantially as set forth.

2. In a lasting-machine, a finger-carrier consisting of a cylindrical tube, a plurality of separate bearing-pieces mounted and adapted to be turned within the tube to adjust the fingers, an end screw for forcing together the clamping-pieces, and means whereby the end clamping-piece is prevented from being turned by the action of said screw, substantially as set forth.

3. In a lasting-machine, the combination, with the carrier-tube V^5 , of the clamping-pieces v^2 , provided with bearings v^3 , an end clamping-piece v^7 , having a sliding connection with said tube and held from turning therein, a clamping-screw V^7 , fingers V^2 , and means for supporting and actuating the carrier, substantially as set forth.

4. In a lasting-machine, the combination, with the side levers, of holders mounted and carried upon the upper ends of the levers and having universal clamp-joints, a carrier tube or frame adapted to be mounted and secured in and by the parts of said joint, separate clamping-pieces fitting said carrier and adapted to receive separate lasting-fingers, and means for forcing said clamping-pieces together, substantially as set forth.

5. In a lasting-machine, the combination, with the side levers, of lasting-finger carriers mounted upon and carried by the free ends of said levers, clamping-pieces fitting said carriers and adapted to receive separate lasting-

fingers, and means for forcing said clamping pieces together, substantially as set forth.

6. In a lasting-machine, the combination, with the side levers, of oscillating holders mounted upon their free ends, stops for arresting and causing the oscillation of said holders, a lasting-finger carrier mounted in the holder, and separate bearing-pieces mounted in the carrier and adapted to secure separate lasting-fingers, substantially as set forth.

7. In a lasting-machine, the combination, with the side and end levers, of a longitudinal screw-shaft provided with right and left hand threads, nuts engaging said threads and connected with the lower ends of the end levers, transverse slide-shafts connected with the lower ends of the side levers, and connections between said transverse shafts and said longitudinal power-shaft, substantially as set forth.

8. In a lasting-machine, the combination, with the side and end levers, of a longitudinal rotary power-shaft having right and left screw-threads, nuts engaging said threads, slide hinge-joints connecting the end levers with said nuts, transverse shafts or slides, slide hinge-joints connecting said slides with the side levers, and angle-levers connected with said transverse slides and with one of the screw-threads of said power-shaft, substantially as set forth.

9. The support for the herein-described lasting-machine, comprising the lateral extensions A', the longitudinal bearing-plates a⁵, the transverse bearing-plates a', the central bearing-bracket a⁹, and the longitudinal guides a¹⁸, having the longitudinal T-groove a⁸, longitudinal slots a¹¹, and the transverse slots a¹⁰, substantially as set forth.

10. The support for the herein-described lasting-machine, comprising the top, the rigid flanged pieces A¹¹, adapted to be bolted thereto, the sheet-metal legs A², having the side flanges a³² and secured to said pieces, the con-

necting-frame A⁴, the back plate A⁶, the doors A⁷, hinged on said flanges, and the bases A¹², fitting the lower ends of said legs, substantially as set forth.

11. The support for the herein-described lasting-machine, comprising the combination, with the rigid top, of the sheet-metal legs A², having side flanges a³² and connected with the top, shelves A³, having upwardly-turned edges a¹⁹ and secured within and stiffening and connecting said legs, a plate closing the back of the table, and a hinged door or doors adapted to close the front of the table between said leg-flanges, substantially as set forth.

12. The support for the herein-described lasting-machine table, comprising the combination, with the rigid top, of the sheet-metal legs connected therewith and having the vertical side flanges a³² and the vertical rabbets a²² a²³, shelves fitting within and connecting said legs, a back plate fitting within the rabbit a²², and a door or doors fitting within said rabbit a²³ and adapted to close the space at the front of the table between the leg-flanges, substantially as set forth.

13. In a lasting-machine, the combination, with the lasting devices or clamps, of a longitudinal screw power-shaft provided at its end with a hand wheel or crank, connections between said clamps and shaft, a vertically-movable head provided with lasting-pliers, and a horizontally-rotating hand wheel or crank adapted to lower said head, whereby the operator while turning the former crank may stand at the side of the machine and close to its vertical axis and to the head-low-ering crank, substantially as set forth.

In testimony whereof I affix my signature in the presence of two witnesses.

ISAAC N. FORBES.
